(57) **CLAIM**

The ornamental design for an autoinjector with removable autoinjector cap, as shown and described.

DESCRIPTION

FIG. 1 is a perspective view showing our new design for an autoinjector with removable cap, with the cap attached; FIG. 2 is a top plan view thereof; FIG. 3 is a bottom plan view thereof; FIG. 4 is a front plan view thereof; FIG. 5 is a right-side elevation view thereof; FIG. 6 is a rear elevation view thereof; FIG. 7 is a left-side elevation view; and, FIG. 8 is a perspective view thereof with the cap removed. The dashed lines showing portions of the autoinjector with removable autoinjector cap are included for the purpose of illustrating environment and form no part of the claimed design.
